UNITED STATES PATENT OFFICE.

WILLIAM P. DE SAUSSURE, JR., OF ENGLEWOOD, NEW JERSEY.

INDEX RACK.

Application filed October 21, 1924. Serial No. 744,879.

This invention relates to visible index and information racks of the kind known as drop-pocket racks, which comprise a series of card pockets inclined to the longitudinal dimension of the rack so that the pockets are in overlapping relation and adapted to hold cards or sheets with a narrow upper portion of each card exposed. It is for many uses desirable that such index racks shall be provided with means for holding certain cards and signal devices associated with individual pockets more or less permanently, while permitting such cards, or certain of them, to be removed and replaced with others when desired. Such more or less permanent cards and signal devices may be, for example, number cards and room data cards and signal devices of racks used as hotel room racks.

An object of the present invention is to provide means for holding such more or less permanent cards and devices in drop-pocket racks in which the partition plates between the pockets of the completed or assembled rack are not slideable or separately removable in the ordinary use of the rack. Such racks may be termed "fixed pocket racks". For holding the more or less permanent cards and signal devices associated with individual pockets of such fixed pocket racks, I provide detachable card holders, or pocket tops, which fit on to the tops of the pocket partition plates and are removable therefrom to permit cards carried thereby to be changed or to permit the holders to be replaced by holders carrying other cards as desired.

A further object of the invention is to provide an improved construction of drop-pocket rack in which the pockets are formed by flanged plates, or card supports, assembled in a rack frame in overlapping superposed relation. Fixed pocket racks are conveniently made by assembling the card supports in the rack frame and securing them in position by holding means engaging the end supports so that the supports are not movable individually or in blocks longitudinally of the frame in the use of the rack. Features of the invention might be employed in index racks in which the card supports are slideable in the completed rack. When the rack is provided with an improved pocket top or card holder, however, there is no need of having the card supports slideable in the rack frame.

A full understanding of the invention can best be given by a detailed description of an approved form of index rack embodying the invention, and such a description will now be given in connection with the accompanying drawings which illustrate a hotel room rack made in accordance with the invention and a modification thereof. In said drawings:

Fig. 1 is a front elevation of such an approved form of my improved index rack;

Fig. 2 is a vertical section on line 2—2 of Fig. 1;

Fig. 3 is a partial top plan view of the index rack, the top member being omitted;

Fig. 4 is an enlarged vertical section on line 4—4 of Fig. 1;

Fig. 5 is a horizontal sectional view of one of the card supports taken on line 5—5 of Fig. 4, but on a scale intermediate between that of Fig. 1 and Fig. 4;

Fig. 6 is a perspective of one of the card supports;

Fig. 7 is a perspective of one of the card and signal holders;

Fig. 8 is a perspective of a room number card;

Fig. 9 is a perspective of a signal slide;

Figs. 10 and 11 are perspectives of two transparent panels;

Fig. 12 is a perspective of a room data card;

Fig. 13 is a perspective of a color signal card;

Fig. 14 is a perspective of a name card;

Fig. 15 is an enlarged perspective view of an end portion of one of the card and signal holders showing the manner in which some of the parts are mounted in the holder;

Fig. 16 is a front view of a card support provided with another form of the card and signal holder;

Figs. 17, 18 and 19 are partial front views of the device shown in Fig. 16, but showing the signal device in different positions;

Fig. 20 is a section on line 20—20 of Fig. 18;

Fig. 21 is a perspective of a color signal strip; and

Fig. 22 is a partial front view of a card support having another form of the card holder.

Referring to the drawings, and first to Figs. 1 to 15, the index rack comprises a rack frame 10 and a plurality of card supports mounted in the frame in overlapping superimposed relation, forming a plurality

of card holding pockets. The rack frame 10, formed most desirably of sheet metal, comprises a back plate 11 and two parallel sides 12 and 13 which extend forward from the back plate. The edge portions of the sides 12 and 13 are bent to form inwardly and rearwardly extending flanges 14 and 15, the rearwardly extending portions of which are spaced from the sides, and the edges of which are spaced from the back plate 11 a distance which depends upon the width and inclination of the card supports. The bottom edge of the back plate is provided with a forwardly extending flange 16 having an upturned edge 17.

The card supports 20, one of which is shown separately in Fig. 6, are made of sheet metal or other suitable sheet material cut and bent to form a rectangular plate 21 having at its bottom edge a straight flange 22 extending forward at right angles to the plate 21 and having at each end a forwardly extending flange 23. The bottom and end flanges all extend the same distance from the plate 21 and serve as spacing flanges for engaging the back face of the adjacent card support when the supports are assembled in the rack frame, and the bottom flanges of the card supports also form the bottoms of the pockets between adjacent assembled card supports. The card supports are of a length to fit freely between the sides of the frame 10 so that they may be slid into place in the frame. In order that the end spacing flanges 23 shall surely engage the back face of the adjacent support, they are formed with inwardly turned edges 24. The flanges 23 most desirably do not extend all the way down to the bottom edge of the plate 21, the lower portion of the plate being slightly cut away as shown at 25 to avoid possible interference with the setting of the card supports in the frame and with relation to each other.

The card supports are also formed with rearwardly projecting lugs 26 stamped out from the back plate 21 and arranged in line parallel to the bottom edge of the plate and spaced from the bottom edge a distance equal to the distance which it is desired the upper portion of the support shall project above the top of the next lower support. In the assembled device the bottom flanges 22 of successive card supports rest on the lugs 26 of the support next below, the lugs 26 thus serving to determine the spacing or extent of overlapping of the assembled card supports. The lugs 26 desirably project a distance slightly less than the width of the flanges 22. A notch 27 is formed in the upper edge of each card support near each end thereof, the space between these notches being equal to the distance between the inwardly extending flanges 14 and 15 of the frame.

In assembling the card supports in the

rack frame, the supports are inserted in the frame one after another from the top. The lowermost, or first inserted card support, rests with its bottom on the flange 16 of the rack frame and inclined forwardly with its upper edge resting against the edges of the flanges 14 and 15. The following card supports are slid into place, each successive support coming to rest with its bottom flange 22 supported by the lugs 26 of the card support next below it and with its flanges against the back of the support next below and its upper edge against the frame flanges 14 and 15, the plates 21 of the card supports being thus spaced apart and card-receiving pockets being formed between the successive plates which become partition plates between the pockets. The width of the bottom flanges 22 is so proportioned with relation to the distance of the lugs 26 from the bottom of the card supports and the inclination of the card supports when assembled in the frame that when the supports are pressed together the bottom flange of each card support will slightly wedge between the back plate of the rack frame and the plate 21 of the card support next below. When the rack frame has been filled with the required number of card supports and the supports properly pressed together and consolidated within the frame, a top holding member 30 formed to press against the back of the uppermost card support in the frame is placed and secured in position. This top member may, as shown, be formed from a piece of sheet metal bent to provide a wedge to enter between the back plate of the frame and the back of the uppermost card support, and may be secured to the back plate of the frame by screws 31.

When the card supports are so positioned within the rack frame, the upper portions of the end flanges of the several supports extend between the inwardly-turned frame flanges 14 and 15 and the frame sides 12 and 13, and the edges of the flanges 14 and 15 are received in the notches 27 formed in the upper edge of the supports. Not only, therefore, are the card supports firmly held in position in the rack frame, but the inwardly turned side flanges of the frame are in turn held by their engagement in the notches 27. The provision of the inwardly turned flanges on the sides of the rack frame not only add to the appearance of the device as a whole but largely increase the strength of the frame, especially when so held by the notches 27, and the frame may therefore be made of thinner material than would otherwise afford sufficient strength.

The plates 21 of the card supports, that is, the partition plates at the rear of the pockets in the completed rack, are provided with detachable card holders 40. Each such card holder is formed from a strip of sheet metal folded lengthwise to provide a narrow

5 pocket having a front wall 41, a back wall 42, and an inner wall or flange 43 turned upward from the bottom of the front wall. The holder is positioned on the upper portion of the plate 21 of the card support to which it is attached by entering the edge of the plate 21 between the back wall of the holder and the flange 43, and then forcing the holder down on the plate. When the 10 holder is off from the card support the flange 43 lies flat against the back wall 42 so that these parts are forced apart by the plate 21, and by pressing against the plate serve to clamp the holder firmly on the plate 15 while permitting it to be readily removed wholly or partly therefrom when desired. The back wall 41 of the holder is desirably extended downward somewhat beyond the bottom of the holder as shown for convenience in placing the holder on the support. 20 The holders are desirably of sufficient length to extend all the way across the top of the support between the frame flanges 14 and 15.

The front wall 41 of each holder is formed 25 with a sight opening or openings for exposing cards or devices mounted within the holder between its front wall and the inner wall 43. In the hotel room rack illustrated by Figs. 1 to 15, the card holders are designed to carry each a room number card, a 30 room data card and a signal device, and the front wall of each holder has an opening 44 at the left hand end of the holder and an opening 45 in its middle portion. The width 35 of these openings is slightly less than the width of the pocket within the holder so that retaining flanges are left at the top and bottom of the openings.

Each holder is provided in the rack shown 40 with a room number card 50, a room data card 51, a signal card 52, and a signal slide 53. These cards or parts are inserted into each holder from the ends thereof and with the exception of the slide 53 their position 45 is not changed in the holder during the ordinary use of the index rack. They are made of suitable width so as to enter the pocket of the holder but to be held therein by the top and bottom flanges of the sight openings.

50 The signal card 52, which is a short strip of colored paper or other suitable material is inserted into the holder from the left hand end and when in position extends from the end of the holder as far as the inner end of 55 the opening 44. The signal slide 53, which may be made of metal and has a projecting tab 54 at one end, is inserted in front of the signal card with its tab 54 at its inner end. The room number card 50 is then inserted 60 in front of the slide and positioned at the outer end of the opening 44. The room number card is of a length slightly greater than one-half the length of the opening 44, and the signal slide is of a length greater than

65 the distance from the end of the room number card to the inner end of the opening, the room number card and signal slide being desirably of equal length. The tab 54 of the slide projects through the opening 44 and by means of this tab the slide may be moved to 70 the right to cover, or to the left to expose, the portion of the signal card which extends inward beyond the end of the room number card. The outer lower corner of the slide is 75 cut away as shown for a purpose to be explained. If desired, a protecting strip or panel 55 of transparent material may be placed in the holder in front of the room number card. The room number card, signal card, and transparent panel are locked in position in the holder by crimping down the end of the lower flange of the holder pocket as 80 shown at 56, Fig. 15. This will not lock the slide 53 owing to its having its lower outer corner cut away, and the slide will therefore 85 be free to be moved lengthwise of the holder. Its movement is limited by engagement of its tab 54 with the inner edge of the card 50 and the inner edge of the opening 44 respectively. The flange at the upper edge of the 90 opening 44 to the right of the inner end of the card 50 and panel 55 may be crimped down slightly as shown in Fig. 15 in order to better guide the slide in its movement and also to prevent the card 50 and panel 55 from 95 moving inward with the slide if the locking of these parts by the crimp 56 should be defective.

The room data card 51, which is a strip bearing desired information as to the price 100 and equipment of the room, is inserted in the holder from the right hand end and is viewed when in position through the opening 45. A protecting strip or panel 57 of 105 transparent material may also be placed in the holder in front of the room data card if desired.

When the card holders are positioned on the plates 21 of the assembled card supports, the ends of the holders will be sufficiently 110 covered by the frame flanges 14 to prevent any accidental outward movement of the cards carried by the holders. When it is desired to change the room data card of the card holder, or pocket top, of any pocket, it 115 is only necessary to raise the right hand end of the particular holder sufficiently to permit the room data card to be withdrawn and one containing the desired information inserted, and then press the holder down 120 again into position. If it should be desired to change a room number or even to make some change in the signal device, this may readily be done by removing the particular card holder, making the desired change, and then returning it to its place; or a different holder may be substituted in its place.

125 The guest cards 60, which may bear the

name and address of the guest and the number of the room occupied and other desired information, or other temporary cards, are simply dropped into the pockets to which they belong, each guest card being placed in the pocket marked with the room number of the room to be occupied by the guest whose name appears on the card. These cards are desirably of a width, or height, such that their upper portions will extend in front of the openings 45, and they should be of less length than the pockets so that they may be placed in the pockets without covering the room number cards. They should be of a length not greater than the distance between the right hand frame flange 15 and the tab 54 of the signal slide when the slide is in its left hand position, but greater than the distance from the right hand flange 15 to the tab of the signal slide when the slide is in its right hand position, so that when the slide is in its position to the right to cover the colored signal card, the slide tab 54 will interfere with the placing of a guest card in the pocket, and, on the other hand, when a guest card is in place in a pocket with the slide moved over to the left, the card will prevent the slide from being moved over to the right.

In the use of the hotel room index rack which has been described, the colored signal card showing through the sight opening 44 of any pocket top indicates that the room with the number of which that pocket is marked has not been sold. See the pocket top of uppermost pocket in Fig. 1. When a room is sold or engaged the clerk moves the signal slide of the corresponding pocket to the right to cover the signal card, as shown for the pocket third from the top in Fig. 1. When on arrival of the guest the guest card 60 is made out, the signal slide of the pocket corresponding to the room the guest is to occupy is moved to the left and the guest card is inserted in the pocket. See fourth pocket from the top in Fig. 1. It will be noted that it is necessary to move the signal slide to its left hand position in order to permit the guest card to be inserted in the pocket. When a guest card has been inserted in a pocket the upper portion of the card bearing the name of the guest will be visible, indicating that the corresponding room is occupied and by whom. When the guest leaves, the guest card is removed and folded and again placed in the pocket at the right hand end of the pocket, as shown for the second pocket from the top in Fig. 1. The color signal will then be visible, indicating that the room is vacant and unsold, and the folded guest card will indicate that the room has not yet been made up ready for use. When the clerk is notified that the room has been made up, he removes the folded card, and the pocket top then appears

as shown for the uppermost pocket in Fig. 1, indicating that the room is made up and unsold.

Card holder pocket tops of a modified form are shown in Figs. 16 to 21. In the card holders shown in these figures, the sight opening 44' at the left hand end of the card holder is made only long enough to hold the number card 50. A plate 70 similar to the signal slide 53, having a forwardly projecting tab 71, is placed in the holder back of the number card with its tab projecting at the end of the opening 44', and serves as a guide or positioning device for the guest card to prevent it from extending over the number card, serving also to prevent the number card from sliding too far into the holder. The flange at the edge of the sight opening may be crimped down to hold the number card and plate 70 in place, but this is not necessary as these parts will be held from outward movement by the frame flange 14 when the holder is positioned on the partition plate of a card support mounted in the frame. A transparent panel or piece 55 may be placed in the holder in front of the number card. The central opening 45' is located midway between the right hand end of the holder and the inner end of the opening 44'. A room data card 51' is placed in the holder to be viewed through the sight opening 45' and is made long enough to extend from the right hand end of the holder to the end of the plate 70, and in front of the room data card there is inserted a sliding signal strip 72 which is of transparent material and is shorter than the room data card and has its end portions 73 and 74 colored, preferably different colors. The uncolored central portion of the slide 72 is desirably of the same length as the sight opening 45' so that when the strip is positioned as indicated in Fig. 18, no color will be visible through the sight opening. By sliding the signal strip 72 to the right or to the left, one or the other of its colored end portions will be brought into position to show at one or the other of the end portions of the sight opening. The slide may be so operated by the finger or by means of the rubber tip of a lead pencil or otherwise. The permissible movement of the signal slide desirably bears such relation to the length of the sight opening 45' that the central portion of the room data card of sufficient length to bear desired data will always be visible through the uncolored portion of the slide.

In using the index rack when equipped with pocket tops such as shown in these figures, the position of the signal slide as shown in Fig. 18 without any colored portion of the slide showing through the sight opening 45' may be used to indicate that an unoccupied room is made up an unsold.

When the room is sold, the slide is moved to the right to display its colored portion 73 at the left hand end of the sight opening. Then when the room is occupied, the guest card is placed in the pocket and its upper portion covers the sight opening 45' of the pocket top as shown in Fig. 16. When the guest leaves, the guest card is removed and the signal slide is moved to the left so that its other end 74 shows at the right hand end of the sight opening as shown in Fig. 17, indicating that the room is unsold and not yet made up. When the room has been made up, the slide is moved to its central position in which no color is visible through the sight opening.

In Fig. 22 there is shown a simplified form of pocket top which serves as a holder for a room number card only, but has no provision for a signal device or for holding a room data card.

It is sometimes desirable to have the room rack or other index rack arranged with unnumbered secondary or auxiliary pockets adjacent to some or all of the numbered pockets, such auxiliary pockets being useful for receiving cards bearing information as to future reservations, etc. The partition plates of such auxiliary pockets may, in order to give the entire rack a uniform and attractive appearance, be provided with blank pocket tops similar to the card holding pocket tops but without sight openings or signal devices. Such a blank pocket top 75 is shown between the pocket tops marked with the room numbers 145 and 146 in Fig. 1.

What I claim is:

1. An index rack, comprising a plurality of partition plates in overlapping superposed arrangement providing a plurality of card pockets, and detachable card-holding pocket tops on the partition plates.

2. An index rack, comprising a plurality of partition plates in overlapping superposed arrangement providing a plurality of card pockets, and detachable pocket tops on the partition plates provided with marks for identifying the individual pockets and formed to serve as card holders for cards removably placed therein.

3. An index rack, comprising a plurality of partition plates in overlapping superposed arrangement providing a plurality of card pockets, and detachable pocket tops on the partition plates formed to serve as holders for cards which are not removed in ordinary use of the rack, the pocket tops being formed to hold such cards against removal when the pocket top is positioned in the rack and to permit removal thereof when the pocket top is moved from its normal position in the rack.

4. An index rack, comprising a plurality of partition plates in overlapping superposed arrangement providing a plurality of

card pockets, and detachable pocket tops on the partition plates each provided with a movable signal device and formed to serve as a card holder.

5. An index rack, comprising a plurality of partition plates in overlapping superposed arrangement providing a plurality of card pockets, and detachable pocket tops on the partition plates formed to extend longitudinally along the top of the partition plates and having card pockets therein open at the ends thereof and sight openings for viewing the cards in the pockets thereof.

6. An index rack, comprising a plurality of partition plates in overlapping superposed arrangement providing a plurality of card pockets, and detachable pocket tops on the partition plates formed of sheet material bent to provide a front wall and a downwardly extending rear wall and an upwardly extending inner flange with a card pocket between the front wall and the inner flange and having a sight opening in the front wall, the rear wall and the inner flange being adapted to receive between them the top edge portion of the pocket partition plate and to bear against said top edge portion.

7. An index rack, comprising a plurality of partition plates in overlapping superposed arrangement providing a plurality of card pockets, and detachable pocket tops on the partition plates formed of sheet material bent to provide a front wall and a downwardly extending rear wall and an upwardly extending inner flange with a card pocket between the front wall and the inner flange and having a sight opening at one end and a signal card and a room number card positioned to be viewed through said sight opening and a signal slide movable to cover or uncover the signal card, the rear wall and the inner flange being adapted to receive between them the top edge portion of the pocket partition plate and to bear against said top edge portion.

8. An index rack, comprising a plurality of partition plates in overlapping superposed arrangement providing a plurality of card pockets, and detachable pocket tops on the partition plates formed of sheet material bent to provide a front wall and a rear wall and an inner flange with a card pocket between the front wall and the inner flange and having a sight opening in the front wall at one end thereof, a number card positioned to be visible through a portion of said sight opening, and a signal slide mounted behind the number card and having a projection extending forward through the sight opening and movable away from and toward the number card.

9. An index rack, comprising a plurality of partition plates in overlapping superposed arrangement providing a plurality of

card pockets, and detachable pocket tops on the partition plates formed of sheet material bent to provide a front wall and a rear wall and an inner flange with a card pocket 5 between the front wall and the inner flange and having two sight openings in the front wall, one of said sight openings being at one end of the wall, a number card positioned to be visible through an outer portion 10 of the end sight opening, a signal slide mounted behind the number card and having a projection extending forward through said sight opening and movable toward and away from the number card, and a data card positioned to be visible through the other sight opening.

10. An index rack, comprising a plurality of partition plates in overlapping superposed arrangement providing a plurality 20 of card pockets, and detachable pocket tops on the partition plates each provided with a signal device movable longitudinally of the pocket top and having a forward projection which when the signal device is in 25 one position serves as a guide or positioning device for cards deposited in the pocket and prevents such cards from covering a part of the pocket top reserved for an identification mark and which when the signal 30 device is moved from such position interferes with the placing of the cards in the pocket.

11. An index rack, comprising a plurality of partition plates in overlapping superposed arrangement providing a plurality of card 35 pockets, and detachable pocket tops on the partition plates, said pocket tops being provided with members slidably mounted therein and adapted to control the display 40 of color signals and having projecting parts adapted to interfere with the placing of cards in said card pockets except when said parts are in predetermined positions.

12. An index rack, comprising a rack 45 frame, a plurality of partition plates mounted in the rack frame in inclined overlapping superposed relation and having bottom flanges and end flanges for engaging adjacent plates to form a series of card-holding 50 pockets, and means for holding the plates pressed together in assembled position in the frame.

13. An index rack, comprising a rack frame, a plurality of partition plates mounted in the rack frame in inclined overlapping superposed relation and having bottom flanges and end projections for engaging adjacent plates to form a series of card holding 55 pockets, means for holding the plates pressed together in assembled position in the frame, and detachable card holding pocket tops on said plates.

14. An index rack, comprising a rack frame having parallel sides provided with 60 inwardly and backwardly turned flanges,

and a plurality of partition plates mounted in the rack frame in inclined overlapping superposed relation and having bottom flanges and forwardly extending end flanges 70 for engaging adjacent plates to form a series of card holding pockets, the upper portions of the end flanges extending between the backwardly turned flanges of the frame and the frame sides.

15. An index rack, comprising a rack 75 frame having parallel sides provided with inwardly and backwardly turned flanges, a plurality of partition plates mounted in the rack frame in inclined overlapping superposed relation and having bottom flanges 80 and forwardly extending end flanges for engaging adjacent plates to form a series of card holding pockets, the upper portions of the end flanges extending between the backwardly turned flanges of the frame and the frame sides, and detachable pocket tops 85 on the partition plates extending along the top of the plates from end to end thereof between said backwardly turned end flanges, said pocket tops being formed with narrow 90 card receiving pockets extending longitudinally thereof and open at the ends thereof.

16. An index rack, comprising a rack frame having parallel sides provided with inwardly and backwardly turned flanges, 95 and a plurality of partition plates mounted in the rack frame in inclined overlapping superposed relation with their lower edges against the back of the frame and their upper edges against the backwardly turned 100 frame flanges and having forwardly extending bottom flanges for engaging adjacent plates to form a series of card holding pockets and having rearward projections on which the bottom flanges of adjacent plates 105 rest.

17. An index rack, comprising a rack frame having parallel sides provided with inwardly and backwardly turned flanges, 110 and a plurality of partition plates mounted in the rack frame in inclined overlapping superposed relation with their lower edges against the back of the frame and their upper edges against the backwardly turned frame flanges and having forwardly extending bottom and end flanges for engaging adjacent plates to form a series of card holding 115 pockets, the end flanges of each plate extending above the top of the plate next below and extending between the backwardly turned flanges of the frame and the frame sides.

18. An index rack, comprising a rack frame having parallel sides provided with inwardly and backwardly turned flanges, 120 and a plurality of partition plates mounted in the rack frame in inclined overlapping superposed relation with their lower edges against the back of the frame and their upper edges against the backwardly turned 125

frame flanges and having bottom flanges and forwardly extending end flanges with inwardly turned edges for engaging adjacent plates to form a series of card holding pockets, the end flanges of each plate extending above the top of the plate next below and extending between the backwardly turned flanges of the frame and the frame sides.

19. An index rack, comprising a rack frame, and a plurality of partition plates mounted in the rack frame in inclined overlapping superposed relation and having bottom flanges and forwardly extending end flanges with inwardly turned edges for engaging adjacent plates to form a series of card holding pockets.

20. An index rack, comprising a rack frame having parallel sides provided with inwardly and backwardly turned flanges, and a plurality of partition plates mounted in the rack frame in inclined overlapping superposed relation and having bottom flanges and forwardly extending end flanges for engaging adjacent plates to form a series of card holding pockets, the upper portions of the end flanges extending between the backwardly turned flanges of the frame and the frame sides, and the upper edge of the plates having notches therein adjacent the end flanges for engagement with the backwardly turned flanges of the frame.

21. An index rack, comprising a rack frame having parallel sides provided with inwardly and backwardly turned flanges, and a plurality of partition plates mounted in the rack frame in inclined overlapping superposed relation and having bottom flanges and end projections for engaging adjacent plates to form a series of card holding pockets, the upper edge of the plates being formed with notches to engage with the backwardly turned flanges of the frame.

22. An index rack, comprising a rack frame having parallel sides provided with inwardly and backwardly turned flanges, and a plurality of partition plates mounted in the rack frame in inclined overlapping superposed relation and having bottom flanges and end projections for engaging adjacent plates to form a series of card holding pockets, the plates being formed with parts extending on each side of each of the backwardly turned flanges of the frame.

23. An index rack, comprising a rack frame having parallel sides provided with flanges extending inwardly therefrom and having a bottom support, and a plurality of partition plates mounted in the rack frame in inclined overlapping superposed relation

with their lower edges against the back of the frame and their upper edges extending forward to the inwardly extending side flanges and having bottom flanges and end projections for engaging adjacent plates to form a series of card holding pockets, the bottom plate resting on said support, and a top member removably secured to the rack frame in engagement with the uppermost plate to hold the plates in assembled position in the frame.

24. A detachable pocket top for drop-pocket index racks, formed to fit over the top edge portion of a pocket partition plate and adapted to be positioned on or removed from the partition plate by movement in the plane of the plate and transversely of the top edge thereof, said pocket top being formed to serve as a card holder and provided with a member movably mounted thereon and adapted to control the display of a color signal.

25. A detachable pocket top for drop-pocket index racks, formed to serve as a card holder, and having a projection adapted to serve as a positioning guide for cards deposited in the pocket.

26. A detachable pocket top for drop-pocket index racks, formed to serve as a card holder and provided with a signal slide movable longitudinally thereof and having a forward projection adapted to interfere with the placing of a card in the pocket when in a predetermined position.

27. A detachable pocket top for drop-pocket index racks, formed of sheet material bent to provide a front wall and a downwardly extending rear wall and an upwardly extending inner flange with a card pocket between the front wall and the inner flange and having a sight opening in the front wall, the rear wall and the inner flange being adapted to receive between them the top edge portion of a pocket partition plate and to bear against said top edge portion.

28. A rack, comprising a rack frame having parallel sides provided with inwardly and backwardly turned flanges, and a plurality of partition plates mounted in the rack frame in superposed relation and having end flanges for engaging adjacent plates to form a series of pockets, the front portions of said end flanges extending between the backwardly turned flanges of the frame and the frame sides.

In testimony whereof I have hereunto set my hand.

WILLIAM P. DE SAUSSURE, Jr.
